GRINDING DEVICE

Louis M. Holtz, Chicago, Ill.

Application August 30, 1944, Serial No. 551,865

5 Claims. (Cl. 51-259)

This invention relates to a grinding device primarily designed for attachment to lathes, and has more particular reference to means for mounting a portable grinder upon the tool side of a lathe carriage whereby said grinder will be supported in proper position for engaging its grinding tool with the work.

An important object of the present invention is to provide a device of the above kind whereby the portable grinder is mounted for swinging movement about a vertical axis, and wherein means is provided to yieldingly swing the grinder in a direction to engage its grinding tool with the work, under manual control and with a predetermined pressure.

A further object of the present invention is to provide a device of the above kind which is comparatively simple and durable in construction, readily applicable to existing lathe carriages, and highly efficient in operation.

The present invention consists in the novel form, combination and arrangement of parts hereinafter more fully described, shown in the accompanying drawings and claimed.

In the drawings, wherein like reference characters indicate corresponding parts throughout the several views:

Figure 1 is a fragmentary top plan view illustrating a grinding attachment constructed in accordance with the present invention and operatively mounted upon a lathe carriage.

Figure 2 is a rear elevational view thereof with the grinder omitted for sake of clearness.

Figures 3 to 8, inclusive, are perspective views of various parts of the mounting means for the grinder.

Figure 9 is a fragmentary vertical section taken on the plane of line 9-9 of Figure 1.

Referring in detail to the drawings, the illustrated embodiment of the present device is primarily designed for use upon a lathe carriage which may be of the type shown in the U. S. patent to A. W. Whitcomb, No. 1,169,214, dated January 25, 1916, and which consists of a compound base mounted for movement longitudinally of the bed of the lathe upon ways 6 and including a bottom slide 7, adjustable transversely of the lathe bed, a swivel block 8 mounted on the bottom slide 7, and a tool slide 9 mounted on the swivel block 8. Also, the present attachment makes use of a conventional portable grinder 10 including an electric motor whose casing is provided at one end with a reduced extension 11 constituting a housing for the armature shaft of said motor, and which armature shaft has a projecting end equipped with a chuck 12 in which is secured the shank 13 of a grinding tool 14 of frusto-conical form.

A mount is provided for the portable grinder and includes a rectangular plate 15 having a cen-

tral opening 16 through which passes a pivot bolt 17 that is threaded into the tool slide 9 so as to pivotally mount the plate 15 upon the latter for turning movement about a vertical axis. A further hole 18 may be provided through the plate 15 adjacent the opening 16 to facilitate introduction of a lubricant between the coacting faces of the slide 9 and plate 15 for promoting ease of turning of the latter. Secured to opposite sides of the plate 15 are circular split clamps 19 and 20, respectively, said clamps having projecting attaching arms 21 and 22, respectively, and screws or bolts 23 being passed through openings of said arms 21 and 22 and threaded into socket 24 of the plate 15 for rigidly securing said clamps to said plate 15. The inner opening of each arm 21 and 22 is preferably elongated vertically, as at 25, so as to permit limited vertical adjustment of the clamps 19 and 21 relative to plate 15. The clamp 19 is of a size to embrace the reduced shaft housing portion 11 of the casing of motor 10, while the clamp 20 is larger for embracing the main or body portion of the casing of motor 10. Screws 26 are provided to tighten the clamps 19 and 20 into firm gripping engagement with the casing portions of the motor 10 for rigidly mounting the grinder upon and to the inner side of the plate 15. The vertical adjustment of clamps 19 and 20 may be effected by set screws 27 carried by the arms 21 and 22 in position to impinge the screws 23 that pass through the elongated openings at 25, said latter screws being merely used to hold the arms 21 and 22 against the sides of the plate 15 and being loosened when the set screws 27 are utilized for adjustment.

Attached at one end to the tool slide 9 below the plate 15 is a horizontal inwardly extending bar 28 that projects across the tool carriage to a point beyond the clamps 19 and 20. Attached by screws 29 to the outer or free end of bar 28 is a block 30 having an opening 31 through which slidably extends an adjusting screw 32 having a feed nut 33 threaded thereon at the outer side of block 30. Attached at one end to the inner end 45 of screw 32 is a helical tension spring 34 whose other end is attached by means of a screw 35 to the arm 21 of clamp 19. It will thus be seen that spring 34 acts to turn plate 15 about its pivot bolt 17 in a direction to cause swinging of the clamps 19 and 20 and the grinder carried thereby so that the grinding tool 14 is moved transversely of the lathe bed in a direction to engage said grinding tool with the work or tap 36 upon feeding the carriage longitudinally of the lathe bed toward said work or tap. In practice, the tap is preferably supported in a horizontal position projecting toward the lathe carriage, by means of a work support of the type shown in my co-pending application Serial No. 551,866, filed August 30, 1944.

The swinging movement of plate 15 and parts carried thereby is properly adjustably limited to limit the depth of cut of the tool 14, by means of an adjusting screw 37 threaded through a block 38 carried by the inner side of bar 28 adjacent plate 15, an end of screw 37 being disposed to abut the inner edge of plate 15 to one side of the pivot of the latter. Block 38 is secured to bar 28 by screws 39. At the side opposite that to which bar 28 is attached, tool slide 9 is increased in effective width by attaching a block 40 thereto arranged to directly underlie the adjacent end of plate 15. Block or plate 40 is attached to the tool slide 9 by means of screws 41 passing through openings 42 of said plate or block 40 and threaded into the adjacent side of the tool slide 9.

The device is used to grind a tap coincident with its longitudinal flutes so as to increase the width of the latter without materially increasing the depth of the same. In this way, material is removed from opposite sides of the lands or teeth of the tap to recondition the latter. To do this, the lathe carriage is adjusted to bring the grinding tool beside a flute of the tap at the free end of the latter. The grinder is then thrown into operation, and spring 34 is allowed to yieldingly engage the grinding tool with the tap. As soon as the desired amount of material is removed, the grinding tool is adjusted longitudinally of the tap and the operation is repeated for the full length of the flute. The other flutes of the tap are ground in the same way, whereupon reconditioning of the tap is completed.

It will be seen that spring 34 swings the grinder and its mount in a direction to engage the grinding tool 14 with the work under a predetermined pressure, depending upon the tension of spring 34, which may be varied as required by turning the nut 33 of adjusting screw 32. A construction is thus had for effectively carrying out the stated objects of the invention, and it is believed that the construction, operation and advantages of the invention will be readily apparent to those skilled in the art. Minor changes in details of construction illustrated and described are contemplated, such as fall within the spirit and scope of the invention as claimed. For instance, the device may be incorporated in the construction of a special grinding machine, instead of being designed as an attachment for conventional lathes.

What I claim is:

1. In combination with the tool slide of a lathe carriage, and a portable grinder, means to mount said grinder upon said tool slide including a horizontal plate, means pivotally mounting the plate upon the tool slide for turning movement about a vertical axis, clamps rigidly attached to opposite sides of said plate and projecting laterally therefrom, said clamps embracing the motor casing of the grinder at spaced points, a bar attached at one end to one side of the tool slide and projecting therefrom across the carriage and beneath the grinder beyond said clamps, and a helical tension spring attached at one end to the free end of said bar and at its other end to one of said clamps for yieldingly swinging said plate in a direction to move the grinder for causing yielding engagement of its grinding tool with the work.

2. In combination with the tool slide of a lathe carriage, and a portable grinder, means to mount said grinder upon said tool slide including a horizontal plate, means pivotally mounting said plate

upon the tool slide for turning movement about a vertical axis, clamps rigidly attached to opposite sides of said plate and projecting laterally therefrom, said clamps embracing the motor casing of the grinder at spaced points, a bar attached at one end to one side of the tool slide and projecting therefrom across the carriage and beneath the grinder beyond said clamps, and a helical tension spring attached at one end to the free end of said bar and at its other end to one of said clamps for yieldingly swinging said plate in a direction to move the grinder for causing yielding engagement of its grinding tool with the work, and means to regulate the tension of said spring.

3. In combination with the tool slide of a lathe carriage, and a portable grinder, means to mount said grinder upon said tool slide including a horizontal plate, means pivotally mounting said plate upon the tool slide for turning movement about a vertical axis, clamps rigidly attached to opposite sides of said plate and projecting laterally therefrom, said clamps embracing the motor casing of the grinder at spaced points, a bar attached at one end to one side of the tool slide and projecting therefrom across the carriage and beneath the grinder beyond said clamps, and a helical tension spring attached at one end to the free end of said bar and at its other end to one of said clamps for yieldingly swinging said plate in a direction to move the grinder for causing yielding engagement of its grinding tool with the work, and means to regulate the tension of said spring.

4. In combination with the tool slide of a lathe carriage, and a portable grinder, means to mount said grinder upon said tool slide including a horizontal plate, means pivotally mounting said plate upon the tool slide for turning movement about a vertical axis, clamps rigidly attached to opposite sides of said plate and projecting laterally therefrom, said clamps embracing the motor casing of the grinder at spaced points, a bar attached at one end to one side of the tool slide and projecting therefrom across the carriage and beneath the grinder beyond said clamps, and a helical tension spring attached at one end to the free end of said bar and at its other end to one of said clamps for yieldingly swinging said plate in a direction to move the grinder for causing yielding engagement of its grinding tool with the work, and means to adjustably limit turning movement of said plate under the influence of said spring.

5. In a grinding machine, a portable grinder, a support, a horizontal plate, means pivotally mounting said plate upon the support for turning movement about a vertical axis, clamps rigidly attached to opposite sides of said plate and projecting laterally therefrom, said clamps embracing the motor casing of the grinder at spaced points, a bar attached at one end to one side of the support and projecting therefrom beneath and beyond the grinder and the clamps, and a helical tension spring attached to one of the clamps and the free end of said bar for swinging the grinder about said axis to cause engagement of its grinding tool with the work.

LOUIS M. HOLTZ.
